KNIFE OR SIMILAR ARTICLE OF FLATWARE

John P. Young, Bronxville, N.Y., and Charles A. Arnold, Providence, R.I., assignors to Lyon Incorporated, Detroit, Mich., a corporation of Delaware

Application April 22, 1958, Serial No. 50,577

Term of patent 14 years

(Cl. D54—12)

The essential features of our design reside in the handle portion shown in full lines on the drawing.

The appearance of the opposite face and edge of the handle, not shown, are substantially identical with the face and edge as shown in Figures 1 and 2, with the exception of the upper end of the handle where one handle face is offset away from the handle as compared to the opposite handle face.

We claim:

The ornamental design for a knife or similar article of flatware, substantially as shown and described.
